UNITED STATES PATENT OFFICE

EDWARD T. O'NEILL, OF EAST CLEVELAND, OHIO, ASSIGNOR TO THE ENAMEL PRODUCTS COMPANY, OF CLEVELAND, OHIO, A CORPORATION OF OHIO

DESIGN FOR A TABLE TOP

Application filed April 10, 1926. Serial No. 17,245. Term of patent 3½ years.

To all whom it may concern:

Be it known that I, EDWARD T. O'NEILL, a citizen of the United States, and a resident of East Cleveland, county of Cuyahoga, and State of Ohio, have invented a new, original, and ornamental Design for Table Tops, of which the following is a specification, reference being had to the accompanying drawing, forming part thereof.

In said annexed drawing:—

Fig. 1 is a plan view of the table top, showing my new design; and Fig. 2 is a sectional view on the line 2—2 of Fig. 1.

I claim:—

The ornamental design for a table top, substantially as shown.

EDWARD T. O'NEILL.
